UNITED STATES PATENT OFFICE

MORRIS SCHAFER, OF PHILADELPHIA, PENNSYLVANIA

GARBAGE-CAN CONTAINER

Application filed November 28, 1928. Serial No. 322,307.

The present invention relates to garbage can containers and particularly to such containers as are adapted to be secured to a fence, or other such defining wall, and in which the arrangement is such that access may be had to the interior of the container from both sides of the fence or wall.

An object of the invention is to provide an improved container of this character.

10 A further object is to provide such a container, with parts so coordinated and related, that the can may be attended from both sides of the fence with a minimum of exertion on the part of the attendants.

15 A further object is to provide a device of this character durable and strong and which may be manufactured at a small cost.

20 A still further object of the invention is to provide a container which, when closed, will be effectively sealed against the escape of odors and against the ingress of insects, rodents and the like.

The garbage can container, constituting my invention and in which the above objects are accomplished, comprises an enclosure, preferably of sheet metal, which may be attached to one side of a fence to cover an opening formed therein for removal and replacement of a garbage can from the alley 25 side of the fence and an open top through which the garbage can may be removed from the container on the inside of the fence. The open top is preferably closed by a double cover, which may be known as the primary 30 and secondary covers, the former being designed to permit removal of the can and the latter to permit insertion of garbage refuse and the like with the primary cover remaining closed.

40 Further facilities, in the operation and attending of the above construction, comprise the addition of accessories so that the secondary cover may be raised by an attendant without the use of the hands and the arrangement of a closure for the opening in the fence in such a manner that the attendant on the alley side may have ready and non-laborious access to the garbage can. The closure for the opening in the fence 45 may be made of sheet metal and the con-

tainer provided with vertical grooves forming slideways for this closure. In this manner the whole device is made complete and need only be attached to the fence with no alterations thereof except the cutting of a 55 hole in the fence and the mounting of a suitable pulley above the opening, over which a cable may be trained if desired to facilitate opening this closure.

Also the cover lids will be so constructed 60 as to prevent the escape of odors from the can by providing suitable flanges thereon which embrace respectively the upper end of the can and a lip ridge around the opening in the primary cover.

65 A detail of the invention of considerable importance is the construction of the secondary cover to facilitate its assembly with a lever arm by which it may be raised and lowered. This feature constitutes a notch 70 in the secondary cover adapted to receive a pin which is removably mounted in the arm and a recess adjacent the arm to provide space for insertion of the pin into an aperture in the arm, in assembling the parts.

75 The accompanying drawings represent an embodiment of the principles of my invention together with a modification of one feature thereof. In these drawings:

Figure 1 is a side elevation of the can container made in accordance with present invention.

Figure 2 is a front elevation of the same, in these two views the fence to which the container is attached is shown fragmentarily.

Figure 3 is a top plane view of the same.

Figure 4 is a vertical section through the fence and through the container on a central line as indicated by the numerals 4—4 in Figure 3.

Figure 5 is a detail fragmentary view showing the construction of a part of the secondary cover and illustrating the manner of attaching the same to the operating lever rod.

Figure 6 is a further detail view illustrative of the same feature as that shown in Figure 5.

Figure 7 illustrates a device similar to that shown in Figures 1 to 6 inclusive but illustrates the same as equipped with a side clo-

sure, slidably laterally of the can, and adaptations of the mounting of the can on the fence contributing to this end.

Figure 8 is a section on the line 8—8 in Figure 7 showing the closure in closed position.

Figure 9 is a plan view of the can as attached to a fence.

Referring to the drawings in detail by reference numerals, 10 designates a fence to which the container 11 is attached by means of flanges 12. The fence is provided with an opening registering with the open side of the container.

15 The lower end of the container is closed by a bottom wall 15 while the upper end is open and provided with a closure designated as a whole by the reference numeral 16.

The closure 16 is supported by a bar 17 attached to the sidewalls of the container as by rivets or bolts as indicated at 17a. Flanges 18 and 19 are preferably formed thereon extending respectively upwardly and downwardly from the bar and a primary cover 20 25 hingedly secured to the bar 17 as by the pivotally connected ears 21 and 22 formed respectively upon the bar 17 and the cover 20.

These ears are made to project at opposite inclinations and to have their extremities 30 overlapping as shown in Figure 3 of the drawings and are adapted to be secured together in pairs by bolts 23 extending through aligned apertures in the ears and held against displacement by nuts 24.

35 The primary cover is provided marginally with a groove 25 formed by two downwardly projecting ribs 26 and 27, the former being designed to lie exteriorly of the walls of the container and the other to lie within said

40 walls, the inner flange 27 being of greater extent than the outer flange and being adapted to sit fairly snugly against the inner wall of the container. This arrangement provides an effective seal against escape of odors from the can and the ingress of flies and etc., thereto. The extent of the primary cover permits ready removal of the garbage can placed within the container.

The primary cover is provided with a central opening 28 which is surrounded on the upper surface of the cover with an annular rib 29 and on its underside with a downwardly directed funnel like flange 30 so constructed that it will direct garbage or the like deposited therein into can placed therebelow. Such a can is shown in Figure 4 and designated by the numeral 31.

55 The opening 28 of the primary cover is normally closed by a secondary cover 32 hinged to the primary cover in a manner which will be hereinafter described and provided with a marginal flange 33 extending downwardly and adapted to snugly encircle the rib 29 referred to above. The hinge construction by 60 which the secondary cover is secured to the

primary cover comprises ears 34 formed on the primary cover and an extension 35 extending rearwardly from the secondary cover and preferably formed integral therewith and with a bore 36 through which a rod 37 constituting a part of a lever arm may be passed. This lever arm is extended beyond the side of the primary cover and is formed at its projecting end with a crank arm 38.

The secondary cover 32 is secured to this rod for rotation therewith by means of a pin 39 inserted through an aperture 40 in the rod and resting in a notch 41 formed in the extension 35; this notch being offset from and in communication with a second notch 42 opening in the bottom side of the extension 35.

The arrangement of these notches to the bore through which the rod 37 extends is of considerable importance in the assembly of the parts which is as follows. The rod 37 is projected through the apertures in the ears 34 and through the bore in the extension 35 after the same have been brought into alignment. But before the rod has been extended to its limit at which the shoulder 37a formed thereon will abut against the adjacent ear 34, and while the aperture 40 is lying in the larger notch 42, the pin 39 is inserted into the aperture 40. The rod is then extended to its full limit and the pin brought into the notch 41 where it will be held by the nut 43 which is then threaded to the end of the rod 37 as shown in Figure 3. By this construction the pin 39 will be prevented from dislodgment 100 from the aperture 40 and the rod 37 and will afford connection by which the secondary cover 32 is forced to turn with the rotation of the rod 37.

By this arrangement the assembly of the secondary cover with the primary cover is facilitated and the accidental disconnection of these two parts one from the other is prevented, while the turning of the secondary cover with the rod 37 is insured.

It frequently happens, when the housewife carries the garbage to the garbage can, that both hands are occupied and it is ordinarily necessary for her to set the vessel down which she is carrying in order to lift the cover prior to depositing the garbage in the can 31. The necessity for this I have overcome by pivotally attaching a foot treadle or level on the lower end of the container. Such a treadle is designated at 44 and is connected with the 115 arm 38 through the link 45. This treadle is preferably passed through a slot 46 formed on one of the supporting legs 57 of the container to prevent treadle from becoming distorted or disengaged from the container.

The opening in the fence may be closed by a suitable slide door 47 arranged in suitable sideways 48 formed in and extending vertically with respect to the container and this door may have attached thereto a cable 49 130

passing over a pulley 50 and having a suitable handle 51 at its end which may be grasped by the garbage collector to raise the door 47. The door may be held raised in a suitable manner as by a hook 52 placed above the opening in the fence and in a position suitable to attach the cable thereto. The door may be formed with its upper edge curved over providing a flange 55a adapted to hook over the flange 18 when the door is closed. This assures a tight closing of this side of the can. It will be seen that my can as constructed is of a most sanitary character and that with the various closures as arranged will effectively prevent the escape of fumes from the garbage and will prevent the access of flies to the garbage; which is not only unsightly but also quite unsanitary.

An alternate construction of closure for the fence is illustrated in Figures 7, 8 and 9 of the drawings in which the closure 47b is constructed to slide sideways instead of vertically as in the previous case. A handle 53 is provided on this closure which is constructed to slide on tracks 54 and 56 extending laterally from the rear of the casing 11a one at the top and one at the bottom of said casing.

The track 54 is a continuation of the flange 18, and the closure 47b is provided with a bent over flange 55b slidable on the flange 18 and its continuation in track 54 at the upper end and a flange 57 which is continued in the track 56 at the lower end and secured to the lower edge of the container. The tracks 54 and 56 are of course substantially in the same vertical plane and the left side of the container 11a viewed from the front, is provided rearwardly with a laterally projecting and vertically extending flange or rib 58 and the closure is provided with a lapped over flange 59 providing a groove adapted to receive this rib 58 therein when the closure is in closed position. The other side of the closure 45 is snugly received in a groove 60 formed at the other side of the casing. In this manner the closure is made substantially proof against the escape of odors and against the ingress of flies, gnats, rodents and the like. 50 This type of device is particularly adapted to use with low fences where the construction shown in Figures 1 to 6 inclusive would be out of the question.

In this modification of the device the bar 55 17 is attached to the fence by means of a bracket 61 placed on the end thereof at the side of the container toward the tracks 54 and 56. The bracket 61 is formed so as to straddle the flange 18 and to present no obstruction to the sliding of the closure 47b thereon. The bottom of the container is also attached to the fence by bracket 63 which is formed to bridge across the flanges 56 and 57.

The operation of the device is quite simple. 65 The garbage is placed in the can 31 within

the container and the attendant from the alley side collects the same. In doing so, he slides the closure 47b to the side and removes the can 31, emptying the same and closing the door 47b.

The device in either construction is fly proof, rodent proof and substantially odor proof.

The present embodiments as shown in the drawings are to be considered as merely illustrative of the principles of my invention and I do not wish to be limited in the scope and application of these principles except as I shall be limited by the scope of the appended claims.

What I claim is:

1. In connection with a garbage can, a closure therefor, a rod connected to the closure, said closure having a notch formed eccentrically therein, and a pin extending from the rod and fitting snugly in said notch, said cover having a recess communicating with the notch and opening on the underside of the cover.

2. The combination with a wall having an opening therethrough, a container secured to the inner side of the wall and having an opening in register with the opening in the wall and with a top opening, a receptacle, the said openings being proportioned for the passage therethrough of the receptacle, a closure for the side opening sliding vertically between the wall and the container, a pulley in the wall elevated above the opening of the wall, a cable having connection with the sliding closure within the wall, means for manual engagement with the cable without the wall, and means for engagement with the cable to hold the closure in open position.

In testimony whereof I have signed my name to this specification.

MORRIS SCHARF.
